[57] ABSTRACT

There are disclosed several truck structures for supporting and guiding the body of a railway car on a wide gauge rail track formed of a pair of rails having a track gauge of at least about ten feet, each of the truck structures including a guide bogie carrying both a pair of tandem load wheels and front and rear sets of spring biased guide wheels, and a follower bogie carrying a pair of tandem load wheels, parallelogram linkages or the equivalent interconnecting the two bogies to coordinate the guiding movements thereof; springs are provided for urging the guide wheels into guiding relationship with the associated rail, and several systems are disclosed for providing spring connections between the bogies and the body of the associated railway car.

FIG. 15

RAILWAY TRUCKS

The present invention relates to truck structures for railway cars, and particularly to truck structures for supporting and guiding railway cars on rails having a track gauge of at least about 10 feet.

It is an important object of the present invention to provide a truck structure for supporting and guiding on a pair of railway rails having a track gauge of at least about ten feet one end of the body of railway car, the truck structure comprising a guide bogie including a frame, at least two wheels mounted on the guide bogie frame for engagement with one associated rail to support the guide bogie thereon and for engagement respectively with the opposite sides of one associated rail to guide the guide bogie thereon, a follower bogie including a frame, a load wheel mounted on the follower bogie frame for engagement with the top of the other associated rail to support the follower bogie thereon, linkage structure interconnecting the guide bogie and the follower bogie for coordinating the movements thereof, and mounting structure for connecting the bogies to the body of an associated railway car.

Another object of the invention is to provide truck structure of the type set forth wherein the guide bogie carries both load wheels for engaging the top of the associated rail and a pair of guide wheels for engagement respectively with the opposite sides of the associated rail.

Another object of the invention is to provide improved truck structure of the type set forth wherein each of the bogies includes a mounting block pivotally mounting the frame of the bogie about an axis disposed generally horizontal and transverse to the associated rail, and a body bolster mounted on the mounting block, there preferably being a vertical sliding engagement between the body bolster and the mounting block with spring structures disposed therebetween to absorb and dampen the transmission of shocks therebetween.

Still another object of the invention is to provide a truck structure of the type set forth wherein each of the bogies includes a pair of load wheels mounted in tandem relationship with a pair of parallel connecting links interconnecting the bogies at longitudinally spaced-apart points to provide a parallelogram linkage therebetween.

In connection with the foregoing object, another object of the invention is to provide an improved truck structure of the type set forth wherein the guide bogie has a front pair of guide wheels mounted on the frame thereof in front of the load wheels for engagement respectively with the opposite sides of the associated rail, and a rear pair of guide wheels mounted on the frame thereof to the rear of the load wheels for engagement respectively with the opposite sides of the associated rail.

Another object of the invention is to provide an improved truck structure of the type set forth wherein the guide bogie is provided with two pairs of guide wheels, both pairs of the guide wheels being resiliently urged inwardly toward the associated rail so as to insure engagement therewith; in one preferred embodiment of the invention the forwardly disposed pair of guide wheels is more forcefully urged toward the associated rail than the rear pair of guide wheels.

Another object of the invention is to provide truck structure of the type set forth wherein spring structure is provided that applies progressively higher force urging the guide wheels respectively into engagement with the associated rail as the misalignment of the guide bogie with respect to the associated rail increases, positive stops preferably being provided so as to limit the movements of the guide brackets supporting the guide wheels with respect to the guide bogie frame.

10 A further object of the invention is to provide a truck structure of the type set forth wherein a beam rigidly interconnects a guide bogie and a follower bogie, the beam being respectively connected to the bogies about pivotal axes extending vertically, and the body of the associated car is connected to the beam by spring connections permitting relative spring controlled movement between the body and the beam in both vertical and transverse directions.

15 20 A still further object of the invention is to provide an improved truck structure of the type set forth wherein separate beams are provided on the guide bogie and the follower bogie and pivotally connected thereto about a vertically aligned pivot axis, the other ends of the beams extending inwardly toward each other and being pivotally connected to each other, the body of the associated railway car being connected to the beams by spring structure permitting both vertical and transverse spring controlled movement therebetween.

25 30 In connection with the foregoing object, a still further object of the invention is to provide a truck structure of the type set forth wherein the pivot connection of the beams to the bogies is disposed forwardly with respect to the longitudinal midpoint between the axes of pairs of load wheels respectively mounted on said bogies, the front guide wheels in one such structure being in lateral alignment with the pivotal connection between the guide bogie and its associated beam.

35 40 Further features of the invention pertain to the particular arrangement of the parts of the truck structure, whereby the above-outlined and additional operating features thereof are attained.

45 The invention, both as to its organization and method of operation, together with further objects and advantages thereof, will best be understood by reference to the following specification taken in connection with the accompanying drawings, in which:

50 FIG. 1 is a side elevational view of a railway motor car embodying therein the present invention;

55 FIG. 2 is a horizontal sectional view of the car of FIG. 1 taken in the direction of the arrows along the line 2-2 of FIG. 1;

55 FIG. 3 is a plan view of the truck structure supporting the railway car of FIGS. 1 and 2, the truck structure being shown positioned upon a curved section of the associated railway track;

60 FIG. 4 is an enlarged view with certain portions broken away of the guide bogie forming a part of the forward or lefthand truck structure of FIG. 3;

65 FIG. 5 is a side elevational view of the truck structure of the guide bogie of FIG. 4;

65 FIG. 6 is a front elevational view of the guide bogie of FIGS. 4 and 5;

FIG. 7 is a fragmentary front elevational and diagrammatic view of another improvement of a guide bogie made in accordance with the present invention;

FIG. 8 is a fragmentary front elevational and diagrammatic view of yet another embodiment of a guide bogie made in accordance with the present invention;

FIG. 9 is a fragmentary front elevational and diagrammatic view of still another embodiment of a guide bogie made in accordance with the present invention;

FIG. 10 is a plan view of yet another form of truck structure made in accordance with and embodying the principles of the present invention;

FIG. 11 is an enlarged fragmentary plan view of the guide bogie forming a part of the truck structure of FIG. 10;

FIG. 12 is a side elevational view of the guide bogie of FIG. 11;

FIG. 13 is a fragmentary view in vertical section through the guide bogie of FIG. 12 along the line 13—13 thereof;

FIG. 14 is a plan view of still another embodiment of the truck structure of the present invention;

FIG. 15 is a fragmentary view in vertical section along the line 15—15 of FIG. 14; and

FIG. 16 is a plan view of a modification of the guide bogie of FIG. 14.

Referring now to FIGS. 1 and 2, there is illustrated a railway motor car 50 which incorporates therein the improved truck structure of the present invention, the motor car 50 being disclosed in U. S. Pat. No. 3,285,194, granted Nov. 15, 1966 to Deodat Clejan. As illustrated, the motor car 50 comprises an elongated longitudinally extending rigid underframe 51, of any suitable construction, and an elongated longitudinally extending body 60 carried by the underframe 51. The underframe 51 is of substantially rectangular configuration having a length of at least about one hundred feet and a width of at least about twenty feet, and as illustrated the underframe 51 has a length of about 130 feet and a width of about 23 feet. The underframe 51 is supported adjacent to the opposite ends thereof by a pair of truck structures 100 made in accordance with the present invention, which truck structures 100 will be described in detail hereinafter.

The body 60 is of box-like configuration including a substantially rectangular floor 61 rigidly secured in place directly upon the top of the underframe 51, a front end wall 62, a rear end wall 63 and a roof 64. The top of the floor 61 is supported in a substantially horizontal lower plane disposed about 4 feet-6 inches above the heads of the associated rails 20-30 (the details of the rails 20-30 being explained more fully hereinafter), and the dimensions of the floor 61 are substantially commensurate with that of the underframe 51 positioned immediately below. The front end wall 62 is disposed in an upstanding position and joins the front end of the floor 61 and the front end of the roof 64; similarly, the rear end wall 63 is disposed in upstanding position and joins the rear end of the floor 61 and the rear end of the roof 64; and the top of the roof 64 is disposed in a generally horizontal upper plane positioned about 9 feet above the top of the floor 61. The front end wall 62 has an outwardly convex configuration to minimize wind resistance to forward travel of the car 50; and the front portion of the roof 64 is curved downwardly to join the top of the front end wall 62 for a similar purpose. The roof 64 is also slightly crowned along the longitudinal center line thereof and downwardly toward the opposite longitudinal eave

thereof for the usual water-shed purpose. The rear end 63 is of composite configuration, including an inwardly concave central section 63a and a pair of longitudinally extending and laterally spaced-apart side sections 63b respectively disposed at the opposite rear sides of the floor 61.

The front end of the underframe 51 carries a centrally disposed front coupler 56; and the rear end of the underframe 51 carries a centrally disposed rear coupler 57. The couplers 56 and 57 are of any conventional construction and are matched; whereby the front end of a trailing car 50 may be coupled to the rear end of a leading car 50 via the couplers 56 and 57, so as to accommodate the make-up of a train comprising any suitable number of the cars 50, all in a conventional manner. The configurations of the front end wall 62 and the central section 63a of the rear end wall 63 are substantially complementary; whereby the front end wall 62 of the trailing motor car 50 is nested into the central section 63a of the rear wall 63 of the leading car 50, when two of the cars 50 are coupled together to make-up a train. This arrangement is very advantageous as it further reduces wind resistance to high speed travel of the train.

An upstanding curved partition wall 65 is arranged rearwardly of the front end wall 62 and between the floor 61 and the roof 64 and cooperating therewith to define a passenger compartment 66 therebetween and located in the extreme front end of the body 60. Another upstanding partition wall 67 is arranged rearwardly of the partition wall 65 and between the floor 61 and the roof 64 and cooperates therewith to define a passenger lounge 68 in the front end of the body 60 and positioned immediately behind the passenger compartment 66. Also it is mentioned that the front wall 62 includes substantial wall structure, indicated at 62a, that is formed of transparent material, such as glass, so as to afford persons in the passenger compartment an unobstructed view of the associated track and adjacent forwardly disposed scenery. Further, upstanding partition walls indicated generally at 69 are arranged rearwardly of the rear end wall 63 and between the floor 61 and the roof 64 and cooperating therewith to define two laterally spaced-apart passenger rest rooms 70 and 71 in the extreme rear end of the body 60.

The rear portions of the front end wall 62 are respectively jointed to a pair of laterally spaced-apart upstanding front posts 72 respectively disposed at the opposite sides of the floor 61; and the front portions of the side sections 63b of the rear wall 63 are respectively joined to a pair of laterally spaced-apart upstanding rear posts 73 respectively disposed at the opposite sides of the floor 61. The posts 72 are arranged in lateral alignment with each other and respectively join the floor 61 and the roof 64; and likewise the posts 73 are arranged in lateral alignment with each other and respectively join the floor 61 and the roof 64. A pair of laterally aligned upstanding posts 74 are arranged rearwardly of the posts 72 and at the opposite sides of the floor 61, the posts 74 respectively joining the floor 61 and roof 64; and a pair of laterally aligned upstanding posts 75 are arranged forwardly of the posts 73 at the opposite sides of the floor 61, the posts 75 respectively joining the floor 61 and roof 64. The posts 72, 74, 75 and 73 on each side of the floor 61 are arranged in sub-

stantially equally spaced-apart relation, the spacing between the pairs of posts 72-74, 74-75 and 75-73 being about 35 feet; whereby three pairs of longitudinally spaced-apart doorways are thus formed in each side of the body 60. Also, the central portion of the floor 61 disposed between the partition walls 67 and 69 and accessible to the three pairs of doorways in the sides of the body 60 has a length of about 110 feet and a width of about 23 feet. This central portion of the floor 61 constitutes a storage area including three sections for passenger automobiles, indicated at 80.

Specifically, four of the passenger automobiles 80 may be conveniently stored in each of the storage sections of the central portion of the floor 61, the four passenger automobiles in each storage section being arranged in side-by-side relation with each other and extending laterally of the floor 61. Moreover, the confronting aligned doorways at the opposite sides of each storage section readily accommodate simultaneous loading and unloading of the four passenger automobiles, all as is explained in the U. S. Pat. No. 3,285,194. In each of the storage sections, two pairs of wheel guides 76 are secured rigidly to the floor 61, so as to insure parking of the passenger automobiles 80 in their storage positions alternately with relatively wide and relatively narrow laterally extending spacing therebetween. This arrangement enforces an economical use of each storage section by the four passenger automobiles 80 therein, while preserving adequate spacing between each two adjacent passenger automobiles 80 to accommodate complete opening of the doors on one side of each of the passenger automobiles 80. Also the width of the floor 61 is adequate to provide a passenger aisle adjacent to one side of the floor 61, when the passenger automobiles 80 are stored or parked on the floor 61 with the respective ends thereof located closely adjacent to the other side of the floor 61, as shown in FIG. 2. This arrangement insures that the passengers of the passenger automobiles 80 have access to their automobile 80, to the passenger lounge 88 and to the rest rooms 70 and 71 at all times during the transit of the car 50.

As is best shown in FIG. 4, the three pairs of side doorways into opposite sides of the body 60 are provided with three pairs of side doors 90, each of the overhead suspension type. Specifically, each of the side doors 90 includes a number of panels suitably hinged together at the adjacent abutting edges thereof so that the side door 90 may be readily moved between open and closed positions with respect to the associated side doorway. In each side door 90, at least one of the panels is formed principally of glass, as indicated at 91, so that the passenger in the adjacent passenger automobile may view the exterior.

Further details of the construction of the motor car 50 and the several parts thereof, together with the manner of use in a combination railway and passenger automobile transportation system are set forth in the above mentioned U.S. Pat. No. 3,285,194, and the disclosure thereof is incorporated herein by reference.

It is pointed out that as illustrated the car 50 is adapted to travel upon a pair of tracks including a guide and support rail 20 and a support rail 30, the rail track having an exceedingly wide gauge of at least 10 feet and preferably of about 17 feet, as illustrated. The

right-of-way is preferably arranged so that it does not intersect any railway track or highway at the grade level, with the result that it is designed for high-speed traffic, up to speeds as high as 200 miles per hour.

Referring to FIG. 7, it will be seen that the guide and support rail 20 includes the usual base 21 carrying a laterally centrally disposed and upstanding web 22 that supports on the upper edge thereof an enlarged head 23. It will be understood that the support rail 30 has the same cross-sectional configuration as the guide and support rail 20.

Referring now specifically to FIGS. 3 to 6 of the drawings, there will now be described the details of a first preferred embodiment of the truck structure 100 illustrated as supporting the car 50, the truck structure 100 being made in accordance with and embodying the principles of the present invention. As illustrated, the truck structure 100 includes a guide bogie 101 carrying a body bolster 110 supporting one corner of the railway car 50, a follower bogie 131 carrying a body bolster (not shown) supporting the adjacent corner of the car 50, and a pair of parallelogram linkages 145 interconnecting the bogies 101 and 131 to coordinate the movements thereof. Referring specifically to FIGS. 4 to 6 of the drawings, it will be seen that the guide bogie 101 includes a frame 102 that is generally rectangular in plan view and in side elevational view, the bogie frame 102 including a generally rectangular vertically extending central opening 103 therein and a pair of longitudinally extending openings 104 communicating with the central opening 103 and extending longitudinally therefrom substantially to the adjacent opposite ends of the frame 102. Positioned in the openings 104 respectively are two load wheels 105, each load wheel 105 being supported upon an axis 106 journaled in the bogie frame 102, whereby to mount the load wheels 105 in tandem relationship upon the frame 102 for rotation about essentially horizontal axes disposed transversely of the associated railway track formed by the rails 20 and 30.

Disposed within the central opening 103 is a generally rectangularly shaped mounting block 107 that is provided with a transversely extending axle 108 that is also journaled in the bogie frame 102, the axis of the axle 108 being essentially parallel to the axes of the axles 106, whereby to mount the block 107 for pivotal movement in fore and aft directions with respect to the bogie frame 102. Formed in the mounting block 107 and extending generally vertically therethrough is a cylindrical bore 109.

In order to mount the adjacent corner of the underframe 51 upon the guide bogie 101, a body bolster 110 is provided, the body bolster 110 having a pivot shaft 111 extending downwardly therefrom and into the bore 109 in the mounting block 107, the pivot shaft 111 being shaped complementary to and having a diameter only slightly less than that of the bore 109, whereby the shaft 111 is free to move vertically therein and with respect to the guide bogie 101 and also to pivot about the longitudinal axis thereof and with respect to the guide bogie 101. A coiled spring 112 under compression is disposed between the underside of the body bolster 110 and the top of the mounting block 107 to cushion and dampen the transmission of shocks between the guide bogie 101 and the body

bolster 110. Any suitable means (not shown) may be utilized to connect the body bolster 110 to the overlying and associated corner of the underframe 51, all in the usual manner.

The above-described parts of the guide bogie 101 are adequate to support the adjacent corner of the car 50 upon the underlying guide rail 20, it being noted that the bearing surfaces on the load wheels 105 are cylindrical in shape and flat in the transverse direction. Inasmuch as two of the truck structures 100 are provided, one at either end of the car 50, and each of the truck structures 100 includes both a guide bogie 101 and a follower bogie 131 each provided with a pair of tandem load wheels, the weight of the car 50 is supported at four points. The load at each of the four points is split equally between the pairs of load wheels, such as the load wheels 105, the two wheels in each tandem pair being located a short distance away from each other and resting upon the same rail 20 or 30, as the case may be. There are eight load wheels in all, having no common axles, each pair being contained in a support frame, such as the frame 102. The load wheels, such as the load wheels 105 are flangeless, but these load wheels will provide some guidance due to the adhesion thereof to the rails, but the guidance thus realized would not be positive, even if an independent steering mechanism were provided.

In order to provide positive guidance as well as steering, two spaced-apart pairs of guide wheels 120 have been provided on the guide bogie 101. More specifically, there are provided at each end of the bogie frame 102 cutouts resulting in support portions 115 that carry therein vertically arranged pivot shafts 116. There also are arranged adjacent to each end of the bogie frame 102 an outwardly extending upper arm 117 and an outwardly extending lower arm 118. In order to mount each of the guide wheels 120 upon the bogie frame 102, a supporting guide bracket 122 has been provided therefor, the associated guide wheel 120 being mounted on the guide bracket 122 by a vertically arranged shaft 121 mounted therein. Upper and lower arms 123 and 124, respectively, are provided on the guide bracket 122, the arms 123-124 extending toward the adjacent bogie frame 102 and receiving therebetween an associated support portion 115 having aligned openings that receive an associated pivot shaft 116, whereby pivotally to mount the guide bracket 122 and the guide wheel 120 carried thereby for pivotal movement about a vertical axis and toward and away from the associated rail 20.

A first spring 125 under tension is provided between each pair of the guide brackets 122, each end of the spring 125 having a fastener 126 thereon that engages the adjacent guide bracket 122, the spring 125 serving to urge the attached guide brackets 122 toward one another, and thus to urge the guide wheels 120 mounted thereon toward the adjacent rail 20, and specifically against the side edges of the rail head 23 thereof. Other springs are also provided between the bogie frame 102 and each of the guide brackets 122, two such springs 127 and 128 being provided and disposed respectively between the upper arm 117 and the lower arm 118 and the adjacent guide bracket 122; more specifically, the upper spring 127 is under compression and is disposed between the upper arm 117

and the adjacent side of the associated guide bracket 122, whereas the lower spring 128 is disposed between the lower arm 118 and the adjacent side of the associated guide bracket 122. The springs 127 and 128 in the front of the guide bogie 101 are stiffer than the springs 127a and 128a at the rear of the guide bogie to provide a force sufficient to keep the guide wheels 120 from spreading, as hereinafter will be explained. The bogie frame 102 is provided with an outer positive stop 119 for each of the guide brackets 122, thus positively to limit the outward movement of the associated guide bracket 122 and the attached guide wheel 120 with respect to the centerline of the bogie frame 102. An inner positive stop 129 is likewise provided to serve as a limit for the movement of each guide bracket 122 inwardly toward the longitudinal centerline of the bogie frame 102.

Referring to FIG. 3, it will be seen that the follower bogie 131 includes a frame 132 that is generally rectangular in plan view and in side elevation, the bogie frame 132 including a generally rectangular vertically extending central opening 133 therein and a pair of longitudinally extending openings communicating with the central opening 133 and extending longitudinally therefrom substantially to the adjacent opposite ends of the frame 132. Positioned in the longitudinal openings respectively are two load wheels 135, each load wheel 135 being supported upon an axle 136 journaled in the bogie frame 132, whereby to mount the load wheels 135 in tandem relationship upon the frame 132 for rotation about essentially horizontal axes disposed transversely of the associated railway track formed by the rails 20-30. Disposed in the central opening 133 is a generally rectangular mounting block 137 mounted on an axle 138, the pivot axis of the axle 138 being substantially parallel to those of the axles 136.

Associated with the follower bogie 131 is a body bolster (not shown) having a pivot shaft 141 extending downwardly therefrom, a spring (not shown) like the spring 112 being disposed between the body bolster and the top of the mounting block 137.

In order to transmit the guiding movement of the guide bogie 101 to the follower bogie 131, the pair of links 145 have been provided that interconnect the bogies 101 and 131 at longitudinally spaced-apart points, one end of each link 145 being connected by a pivot pin 146 carried by the arms 117-118 on the guide bogie 101, and the other end of each link 145 being likewise connected by a pivot pin 146 to an upper arm 147 on the frame 132 and a lower arm (not shown) thereon. The links 145 form a parallelogram system interconnecting the bogies 101 and 131 to provide for the necessary wheel articulation when the car 50 is running on a curve in the associated railway track. The load wheels 105 and 135 are flangeless, whereby the entire steering is achieved by the two sets of guide wheels 120 on the guide bogie 101. As explained above, the load wheels 105 and 135 will provide some guidance due to the adhesion thereof to the associated rails 20 and 30, respectively, but the major guidance is provided essentially by the guide wheels 120. As a consequence, both the steering of the load wheels 105-135, as well as positive guidance of the truck structure 100, is provided by the two sets of guide wheels 120. The steering effectiveness of the guide

wheels 120 is increased due to the placement of the two sets of guide wheels farther away from the pivot axis of the pivot shaft 111 than the load wheels 105. Steering action is transmitted to the follower bogie 131 by the parallelogram linkage provided by links 145.

From the above description it will be seen that the truck structure 100 uses the single rail 20 for guidance, whereby if the width of the load wheels 135 is made adequate, the accuracy required in maintaining the gauge tracks 20-30 is greatly reduced. In addition, allowance for rail irregularity is made by the introduction of compliance between the guide wheels 120 and the bogie frame 102, various spring tensions being employed. A relatively light force is applied by the springs 125 to keep both of the associated guide wheels 120 in contact with the rail 20 at all times, when the guide wheel spacing is within the normal tolerance of the railhead 23. On the other hand, a relatively stiff spring force is applied by the springs 127-128 to keep the guide wheels 120 from spreading so far as to disengage from the guide rail 20. Preferably the springs 127 and 128 at the front of the guide bogie 101 are stronger and provide a stiffer spring force than the springs 127a and 128a at the rear of the guide bogie. Each pair of the guide wheels 120 is spring-centered into alignment with the centerline of the associated load wheels 105, and the amount of spring pressure applied by the system including the springs 125, 127 and 128, 127a and 128a is progressively increased as the misalignment of the guide wheels 120 with respect to the centerline of the load wheels 105 is increased. Eventually, positive limits in the form of the positive stops 119 and 129 are encountered, thus to prevent the guide wheels 120 from being disengaged from the guide rail 20. The width of the load wheels 105 and 135 is greater than the full lateral travel of the guide wheels 120, i.e., the full lateral travel of the guide brackets 122 between the positive stops 119 and 129.

The car 50 will run at operating speeds fundamentally only in one direction, so that the same set of guide wheels 120 will always lead and the other set of guide wheels 120 will always trail. The centering spring pressure at the leading guide wheels 120 is preferably made stiffer or greater than that at the trailing guide wheels 120. Thus when a lateral force is applied to the car 50, the difference in spring forces will steer the load wheels 105-135 in such a way that these load wheels 105-135 will resist a major portion of the lateral load (within the adhesion capabilities thereto) and the average forces supported by the guide wheels 120 will be substantially reduced. The maximum load on the guide wheels 120 may nonetheless be equal to the maximum laterally applied force, since the road wheels 105-135 may lose adhesion. The disclosed guiding and steering system is one wherein the flangeless load wheels 105-135 and the guide rollers 120 assist each other whenever possible, and one never interferes with the action of the other.

The system of springs described above serves also to isolate lateral shocks which would otherwise be transmitted to the car 50 due to rail irregularities. Although the combination of the several springs with the mass of the car 50 will unavoidably lead to some oscillations, friction between the rails 20-30 and the load wheels 105-135 will tend to damp out the oscillations.

It will be appreciated that in the truck structure 100 of FIGS. 3 to 6, the guide bogie 101 is constrained against movement fore and aft, movement sideways, and leaning relative to the vehicle underframe 51, but is free to move vertically against the spring 112, for example, to pitch and to yaw.

Furthermore, guiding on both sides of the single narrow rail 20 by use of the guide wheels 120 essentially eliminates the tendency to bind. It is also pointed out that the contact surfaces of the guide wheels 120 are cylindrical in shape whereby the contact surfaces in a vertical direction are flat and engage the opposite sides respectively of the railhead 23.

In order to provide motive power for the motor car 50, it will be understood that one or more of the load wheels 105 and 135 has associated therewith a drive motor (preferably electric) that is connected thereto in a driving relationship. The drive motor may be mounted upon the bogie frame 102 or 132, as the case may be, and preferably each of the load wheels 105 and 135 is so equipped with a drive motor, all is well understood in the art.

There is shown in FIG. 7 of the drawings a first modification of the truck structure 100 described above, there being shown in FIG. 7 only a diagrammatic illustration of a portion of the guide bogie to which there has been applied the numeral 101A. In the truck structure of FIG. 7, the load wheels 105A are mounted respectively on axles 106A that are identical in structure to the like numbered parts in FIGS. 3 to 6 and are mounted in a like manner. The guide brackets 122A carry thereon guide wheels 120A, the guide wheels 120A having cylindrical guide surfaces 125A engaging the adjacent sides of a railhead 23. In addition a flange 126A is provided on the lower edge of the guide wheel 120A. The purpose of the flanges 126A is positively to prevent disengagement of the guide bogie 101A from the rail 20 in a vertical direction if the parts

are tended to be lifted from the rail 20. Normally, the flanges 126A are not in engagement with the rail 20 and are placed in engagement therewith only if all of the parts are lifted with respect to the rail 20. It will be understood that the other elements of the guide bogie 101 described above are incorporated in the guide bogie 101A, and specifically the several springs urging the guide wheels 120A into engagement with the railhead 23 are incorporated therein.

There is illustrated in FIG. 8 of the drawings yet another modification of the truck structure of FIGS. 3 to 6, and there is specifically shown a guide bogie 101B including a frame 102B. The frame 102B carries a pair of angularly inclined wheels 105B provided with a groove 107B extending circumferentially therearound and positioned between a pair of side flanges 108B and 109B. Each of the wheels 105B is mounted on the frame 102B by means of an axle 106B, whereby the wheel 105B rotates about an axis inclined 45° with respect to the horizontal in a plane normal to the longitudinal axis of the rail 20. The flange 108B actually rests upon the top of the railhead 23 and the flange 109B rests against the side of the railhead 23. Such a system provides good guidance with a minimum of friction since the wheels 105B have the same peripheral velocity at the contact points against the top and sides of the railhead 23. The guide bogie 101B also does not

tend to climb off of the rail 20 or gouge thereinto since the contact surfaces are curved and roll against the rail 20. Furthermore, the structure of FIG. 8 permits simple switching structures in the rail 20.

Still another form of the truck structure 100 is illustrated in FIG. 9, there being illustrated a guide bogie 101C which also includes structure to prevent inadvertent vertical displacement between the guide bogie 101C and the rail 20, along the lines discussed above with respect to FIG. 7. In the guide bogie 101C, the load wheel 105C is mounted on an axle 106C, which parts are like the parts 105 and 106 described above with respect to FIGS. 3 to 6. The guide brackets 122C carry guide wheels 120C on the lower ends thereof, each of the guide wheels 120C including a cylindrical guide surface 125C bearing against the adjacent side of the web 22 on the rail 20. The upper each of each of the guide wheels 125C is beveled as at 126C and is in position to engage the underside of the railhead 23 if the guide bogie 101C is inadvertently lifted with respect to the rail 20. As a consequence, the railhead 23 positively prevents the guide wheels 120C from disengaging with the rail 20 even if the load wheels 105C should lift from the railhead 23. It will be understood that the other elements of the guide bogie 101 described above are incorporated in the guide bogie 101C, and specifically the several springs urging the guide wheels 120C into engagement with the railhead 23 are incorporated therein.

In order to improve the riding qualities of the car 50 for passenger service, it may be desirable to maintain the upright position of the several bogie frames. A modification of the truck structure which permits maintenance of the bogie frames in an upright position is illustrated in FIGS. 10 to 13 of the drawings, wherein there is shown a truck structure 200 also made in accordance with and embodying the principles of the present invention. As illustrated, the truck structure 200 includes a guide bogie 201, a follower bogie 231, a body bolster 240 and an I-beam 250 interconnecting the bogies 201 and 231. The guide bogie 201 includes a frame 202 that is generally rectangular in plan view and in side elevational view, the bogie frame 202 including a generally cylindrical horizontal central opening 203 therein and a pair of longitudinally extending openings 204 communicating with the central opening 203 and extending longitudinally therefrom substantially to the adjacent opposite ends of the frame 202. Positioned in the openings 204 respectively are two load wheels 205, each load wheel 205 being supported upon an axle 206 journaled in the bogie frame 202, whereby to mount the load wheels 205 in tandem relationship upon the frame 202 for rotation about a generally horizontal axis disposed transversely of the associated railway track formed by the rails 20 and 30.

In order to provide positive guidance as well as steering, two spaced-apart pairs of guide wheels 220 have been provided on the guide bogie 201. More specifically, there are provided at each end of the bogie frame 202, cutouts resulting in support portions 215 that carry therein vertically arranged pivot shafts 216. There also are arranged adjacent to each end of the bogie frame 202 an outwardly extending upper arm 217 and an outwardly extending lower arm 218. In order to mount each of the guide wheels 220 upon the

bogie frame 202, a supporting guide bracket 222 has been provided therefor, the associated guide wheel 220 being mounted on the guide bracket 222 by a vertically arranged shaft 221 mounted therein. Upper arms 223 and lower arms (not shown) are provided on the guide bracket 222, the arms 223, for example, extending toward the adjacent bogie frame 202 and receiving therebetween an associated support portion 215 and having aligned openings that receive the associated pivot shaft 216, whereby pivotally to mount the guide bracket 222 and the guide wheel 220 carried thereby for pivotal movement about a vertical axis and toward and away from the associated rail 20.

15 A first spring 225 under tension is provided between each pair of the guide brackets 222, each end of the spring 225 having a fastener 226 thereon that engages the adjacent guide bracket 222, the spring 225 serving to urge the attached guide brackets 222 toward one another, and thus to urge the guide wheel 220 mounted thereon toward the adjacent rail 20, and specifically against the side edges of the rail head 23 thereof. Other springs are also provided between the bogie frame 202 and each of the guide brackets 222, two such springs 20 227 being provided and disposed respectively between the upper arm 217 and the lower arm 218 and the adjacent guide bracket 222. Similar to the first described embodiment herein, the front springs 227 in the front of the bogie are preferably made stiffer than the springs 25 227a at the rear of the bogie, for the same reasons set forth above. The bogie frame 202 is provided with an outer positive stop 219 for each of the guide brackets 222, thus positively to limit the outward movement of the associated guide bracket 222 and the attached guide wheel 220 with respect to the centerline of the bogie frame 202. The inner positive stop 229 is likewise provided to serve as a limit for the movement of each guide bracket 222 inwardly toward the longitudinal centerline of the bogie 202.

30 Referring to FIG. 10, it will be seen that the follower bogie 231 includes a frame 232 that is also essentially rectangular in plan view and is likewise rectangular in side elevational view, the frame 232 having a central opening (not shown) extending laterally therethrough and formed like the opening 203 described above. Longitudinal openings 234 are also provided extending forwardly and rearwardly from the central opening, the longitudinal openings receiving therein respectively a 35 pair of tandem arranged load wheels 235, the load wheels 235 being respectively mounted on axles 236 journaled in the bogie frame 232 for rotation about horizontal axes disposed substantially transverse to the rails 20-30.

40 Interconnecting the guide bogie 201 and the follower bogie 231 is an I-beam 250, the ends of the I-beam 250 extending respectively into the central openings, such as the central opening 203 in the guide bogie 201. One end of the I-beam 250 carries an upstanding bearing 207 connected thereto as by welding as at 251 and disposed in the central opening 203 in the bogie frame 202, and the other end of the I-beam 250 carries an upstanding bearing 237 also secured thereto as by welding and disposed in the central opening in the bogie frame 232. A pivot pin 208 is disposed in the bogie housing 202 and extends through the bearing 207 pivotally to mount the bearing 207 on the frame 202, and a pivot

pin 238 likewise extends vertically through aligned openings in the bogie frame 232 and the bearing member 237 pivotally to mount the bearing member 237 on the bogie frame 232. Care is taken to insure that the pivot axes of the pivot pins 208 and 238 are parallel to each other and vertically aligned, whereby the I-beam 250 serves to hold the bogies 201 and 231 in upright positions and fixedly spaced-apart with respect to each other.

A body bolster 240 is provided attached to the lower side of the underframe 51, the body bolster 240 having extending downwardly therefrom a hollow beam 241 formed by a pair of transverse vertically arranged side walls 242, a pair of longitudinal vertically arranged end walls 243 and a bottom wall 244, the end walls 243 having openings 245 therein which receive the I-beam 250 therethrough. The lateral extent of the hollow frame 241 is less than the length of the I-beam 250, whereby there is space between the hollow beam 241 and each of the adjacent bogies to mount a spring retainer 252 on the top of the I-beam 250. There is disposed between each of the spring retainers 252 and the underside of the body bolster 240 a stabilizing spring 253 under compression. There also is provided in the bottom wall 244 of the hollow beam 241 adjacent to each end thereof an opening 246, and extending into each of the openings 246 is an arm 254 carried by the I-beam 250. Each of the arms 254 is provided with a pair of laterally oriented springs 255 under compression that are disposed between the arm 254 and the adjacent surface defining the opening 246. The springs 253 serve to dampen and reduce the transmission of shock in a vertical direction between the truck structure 200 and the body bolster 240 and thus the attached car 50, while the springs 255 serve to dampen and reduce the transmission of shocks in a horizontal direction between the truck structure 200 and the body bolster 240 and thus the attached car 50. It will be appreciated that the I-beam 250 serves as an undersprung beam from side-to-side of the car 50 to which the bogie frames are pivotally connected to permit parallelogram steering. The car body 51 is both vertically and laterally spring suspended relative to the I-beam 250.

There is illustrated in FIGS. 14 and 15 of the drawings a form of truck structure 300 also made in accordance with and embodying the principles of the present invention, the truck structure 300 utilizing guide wheels 320 rotating about axes fixed with respect to the guide bracket 301 on which they are mounted, this truck structure 300 providing improved dynamic stability in guidance. As illustrated, the truck structure 300 includes a guide bogie 301, a follower bogie 331, a pair of interconnection parallelogram tie rods 340-341 and a pair of interconnecting beams 350. As illustrated, the guide bogie 301 includes a frame 302 that is essentially rectangular in plan view and is essentially C-shaped in vertical section and includes an outer vertical wall, a bottom wall and a top wall 303. Two vertically aligned longitudinally spaced-apart sets of openings 304 are provided in the frame 302 to receive therein two load wheels 305, each load wheel 305 being supported upon an axle 306 journaled in the bogie frame 302. The load wheels 305 are thus mounted in tandem relationship upon the frame 302 for rotation about generally horizontal axes disposed transversely of the

associated railway track formed by the rails 20 and 30. The bearing surfaces on the load wheels 305 are cylindrical in shape and flat in the transverse direction.

In order to provide positive guidance as well as steering, two spaced-apart pairs of guide wheels 320 have been provided on the guide bogie 301. More specifically, there is provided on the front end of the bogie frame 302 a pair of forwardly directed arms 322, each of the arms 322 carrying a vertically arranged shaft 321 supporting one of the front pair of guide wheels 320. The rear end of the bogie frame 302 likewise carries a pair of rearwardly directed arms 322, each of the arms 322 carrying a vertically arranged shaft 321 carrying thereon one of the rear guide wheels 320. The parts are arranged so that the two wheels of each pair of guide wheels 320 respectively engage the opposite sides of the guide rail 20.

The follower bogie 331 includes a frame 332 that is also generally rectangular in plan view and is C-shaped in cross section (see FIG. 15). Two pairs of vertically aligned longitudinally spaced-apart openings 334 are provided in the frame 332. Positioned in the openings 334, respectively, are two load wheels 335, each load wheel 335 being supported upon an axle 336 journaled in the bogie frame 332, whereby to mount the load wheels 335 in tandem relationship upon the frame 332 for rotation about essentially horizontal axes disposed transversely of the associated rail track formed by the rails 20 and 30.

Connection is made to the body 310 of an associated railway car essentially through a pair of beams 350, each of the beams 350 carrying upper and lower arms 351 and 352 at one end thereof and carrying an upwardly directed arm 353 at the other end thereof. One of the beams 350 is connected to the guide bogie 301 at a point spaced forwardly of the longitudinal midpoint 307 between the axes of the load wheels 305, and more specifically a pivot pin 308 extends downwardly through and is mounted in the bogie frame 302 and passes through aligned openings in the arms 351-352 of the associated beam 350. When so mounted, the beam 350 extends inwardly toward the longitudinal centerline of the truck structure 300 with the arm 353 extending upwardly and into the space disposed between a pair of depending arms 311 and adjacent to the arm 353 on the other beam 350. The inner ends of the beams 350 are connected by a ball joint 360 which is normally in compression because the two beams 350 act as a compressive member. Disposed between each of the arms 353 and the adjacent arm 311 is a spring 315 under compression, and there also is provided on each of the beams 350 a spring support 356 which supports a vertically arranged spring 316 between the underside of the body 310 and the spring support 356, the spring 316 also being under compression.

The guide bogie 301 and the follower bogie 331 are also connected by a parallelogram linkage system including a pair of shorter tie rods 340 that are pivotally connected to ears 309 on the bogie frame 302 by means of pivot pins 342, and a pair of longer tie rods 341 pivotally connected to ears 339 on the bogie frame 332 by pivot pins 342. Turn buckles 343 adjustably interconnect a short rod 340 to the associated long rod 341, it being noted that the linkages are disposed at the extreme front and rear ends of the bogies 301 and 331.

Additional connections are made to the car body 310 from the beams 350, and specifically a connection in the form of a tie 361 is made from the ball joint 360 to the car body 310, and a pair of longitudinally extending ties 365, respectively, interconnect the beams 350 and the underside of the car body 310.

The thus described truck structure 300 simultaneously provides (1) constraint against roll, (2) freedom of pitch, (3) freedom of yaw, (4) that the line of action for longitudinal loads is along the sagittal center plane of the truck structure 300, (5) that the line of action of transverse loads is through the pivot pins 308 and 338 that are forward of the midpoints 307 and 337 between the load wheels 305 and 335, respectively, (6) and that the line of action of vertical rods is through the midpoints 307 and 337 of the load wheels 305 and 335, respectively. The first condition provides for static stability of the bogies, while conditions (3) and (4) tend to alleviate wear; the remaining conditions (2), (5) and (6) are necessary for dynamic stability. There results a marked dynamic stability during guidance, it being noted, however, that the pivot pins 308 and 338 are biased and positioned for stability in the forward direction only, i.e., in the direction of the arrow, whereby the truck structure 300 may be utilized only if the attached vehicle is to be reversed at low speeds.

Each of the beams 350 is connected to the associated bogie 301 or 331 at two points by the pivot pin 308 or 338, respectively, one connection point being above the other and with the connection points being as high and as low as possible, respectively, with respect to the associated bogie. The inner ends of the two beams 350 meet each other at the sagittal center plane of the vehicle, this meeting being at the ball joint 360 and at a point spaced well above the tie rods 340-341. The ball joint 360 is normally in compression because the two beams 350 act as a compressive member which, together with the tie rods 340-341 that act as tension members, will resist the moment that arises from the fact that the vehicle load is supported inboard with respect to the load wheels 305-335.

Constraints in the longitudinal, i.e., fore and aft, direction are provided at two points between the body 310 and each beam 350, such that a straight line 345 through these two points will intersect the plane of the load wheels 305-335 at the elevation of the railhead 23 or 33, as the case may be. Preferably, one of the points should be at or near the ball joint 360 and the other should be as close as practicable to the pivot pin 308 or 338, as the case may be.

Vertical loads between the body 310 and each beam 350 are transmitted through the springs 316 and are so positioned that the effective line of action of the resultant forces lies in the vertical plane that passes through the ball joint 360 and through the midpoint 307 or 337, as the case may be, between the load wheels 305 and 335, respectively, the vertical plane referred to being designated by the dashed line 346 in FIG. 14. Lateral loads between the body 310 and each beam 350 are preferably transmitted along a line of action in line with the pivot pins 308 or 338, the line of action being high to reduce the coupling between the lateral movement and the roll mode of the body 310.

It will be noted that the guide wheels 320 serve to position the truck structure 300 and the attached car

with respect to the rail 20. The front and rear pairs of guide wheels 320 share the functions of positioning the parts with respect to the rail and at the same time share the function of aiming the load wheels 305.

There is shown in FIG. 16 of the drawings a guide bogie 301A which is a modification of the guide bogie 301 illustrated in FIG. 14. The construction of the guide bogie 301A is substantially identical to that of the guide bogie 301, whereby like reference numerals have been applied to like parts with the addition of the suffix A. The fundamental difference between the guide bogies 301 and 301A lies in the placement of the forward pair of guide wheels, the forward pair of guide wheels 320B in FIG. 16 being positioned in lateral alignment with the pivot pin 308A, and more specifically, the frame 302A has a pair of laterally extending ears 322B on either side thereof in alignment with the pivot pin 308A, the ears 322B supporting vertically extending axles 321B that in turn support the guide wheels 320B thereon. The vertical axes of rotation of the guide wheels 320B are in lateral alignment with the axis of the pivot pin 308A. The guide wheels 320B position the associated car relative to the rail 20 while the aft pair of guide wheels 320A aim the load wheels 305A in the direction of the rail 20, thereby reducing wear. It further is pointed out that two vertical support springs 316A and 316B are provided on the bogie 301A on opposite sides of the beam 350A and supported, respectively, between spring supports 356A and 356B on the beam 350A and the underside of the associated car body.

It further is pointed out that the location of the pivot pins 308 and 338 on the bogies 301 and 331, respectively, forwardly of the longitudinal center points 307 and 337, respectively, reduces oscillations of the truck structure 300 during the operation thereof, such a structure introducing a "castor" effect in the truck structure. This same characteristic is introduced into the guide bogie 301A of FIG. 16 by the placement of the pivot pin 308A thereof forwardly with respect to the longitudinal centerline between the load wheels 305A.

From the above it will be seen that there has been provided a number of truck structures which fulfill all of the objects and advantages set forth above.

While there have been described what are at present considered to be certain preferred embodiments of the invention, it will be understood that various modifications may be made therein, and it is intended to cover in the appended claims all such modifications as fall within the true spirit and scope of the invention.

What is claimed is:

1. Truck structure for supporting and guiding on a pair of railway rails having a track gauge of at least about ten feet one end of the body of a railway car, said truck structure comprising a guide bogie including a frame, a load wheel mounted on said guide bogie frame for engagement with the top of one associated rail to support said guide bogie thereon, a front pair of laterally spaced-apart guide brackets respectively pivotally mounted on the opposite sides of said guide bogie frame and disposed forwardly of said load wheel, a rear pair of laterally spaced-apart guide brackets respectively pivotally mounted on the opposite sides of said guide bogie frame and disposed rearwardly of said

load wheel, a front pair of guide wheels respectively mounted on said front pair of guide brackets in position for engagement respectively with the opposite sides of the one associated rail, a rear pair of guide wheels respectively mounted on said rear pair of guide brackets in position for engagement respectively with the opposite sides of the one associated rail, front spring means mounted on said guide bogie frame for urging said front guide wheels respectively into engagement with the one associated rail to guide said guide bogie thereon, rear spring means mounted on said guide bogie frame for urging said rear guide wheels respectively into engagement with the one associated rail to guide said guide bogie thereon, said front spring means applying greater pressure to said front guide wheels than said rear spring means applies to said rear guide wheels to provide a greater centering pressure at the leading guide wheels than at the trailing guide wheels to reduce the average forces supported by all of the guide wheels, a follower bogie including a frame, a load wheel mounted on said follower bogie frame for engagement with the top of the other associated rail to support said follower bogie thereon, linkage structure interconnecting said guide bogie and said follower bogie for coordinating the movements thereof, and mounting structure for connecting said bogies to the body of an associated rail car.

2. Truck structure for supporting and guiding on a pair of railway rails having a track gauge of at least about 10 feet one end of the body of a railway car, said structure comprising a guide bogie including a frame, a first pair of load wheels mounted on said guide bogie frame in tandem relationship for engagement with the top of one associated rail to support said guide bogie thereon, a front pair of guide wheels mounted on said guide bogie frame in front of said first pair of load wheels for engagement respectively with the opposite sides of one of said associated rails to guide said guide bogie thereon, a rear pair of guide wheels mounted on said guide bogie frame to the rear of said first pair of load wheels for engagement respectively with the opposite sides of the one associated rail to guide said guide bogie thereon, front spring means mounted on said guide bogie frame for urging said front guide wheels respectively into engagement with the one associated rail to guide said guide bogie thereon, rear spring means mounted on said guide bogie frame for urging said rear guide wheels respectively into engagement with the one associated rail to guide said guide bogie thereon, said front spring means applying greater pressure to said front guide wheels than said rear spring means applies to said rear guide wheels to provide a greater centering pressure at the leading guide wheels than at the trailing guide wheels to reduce the average force supported by all of the guide wheels, a follower bogie including a frame, a second pair of load wheels mounted on said follower bogie frame in tandem relationship for engagement with the top of the other associated rail to support said follower bogie thereon, a beam interconnecting said bogies and pivotally connected respectively thereto about vertically extending axes, a body bolster mounted on the body of the associated railway car and extending downwardly to said beam, and spring structure means interconnecting said beam and said body bolster.

3. The truck structure set forth in claim 2, wherein said spring structure includes a first set of springs acting vertically between said beam and said body bolster, and a second set of springs acting laterally between said beam and said body bolster.

4. Truck structure for supporting and guiding on a pair of railway rails having a track gauge of at least about ten feet one end of the body of a railway car, said structure comprising a guide bogie including a frame, a first pair of load wheels mounted on said guide bogie frame in tandem relationship for engagement with the top of one associated rail to support said guide bogie thereon, a front pair of guide wheels mounted on said guide bogie frame for engagement respectively with the opposite sides of one of said associated rails to guide said guide bogie thereon, a rear pair of guide wheels mounted on said guide bogie frame for engagement respectively with the opposite sides of the one associated rail to guide said guide bogie thereon, a follower bogie including a frame, front spring means mounted on said guide bogie frame for urging said front guide wheels respectively into engagement with the one associated rail to guide said guide bogie thereon, rear spring means mounted on said guide bogie frame for urging said rear guide wheels respectively into engagement with the one associated rail to guide said guide bogie thereon, said front spring means applying greater pressure to said front guide wheels than said rear spring means applies to said rear guide wheels to provide a greater centering pressure at the leading guide wheels than at the trailing guide wheels to reduce the average force supported by all of the guide wheels, a second pair of load wheels mounted on said follower bogie frame in tandem relationship for engagement with the top of the other associated rail to support said follower bogie thereon, a first beam pivotally mounted on said guide bogie about a vertically disposed axis positioned between said first pair of load wheels, a second beam pivotally mounted on said follower bogie about a vertically disposed axis positioned between said second pair of load wheels, said beams extending inwardly toward each other and connected to the body of the associated railway car, and linkage structure interconnecting said guide bogie and said follower bogie for coordinating the movements thereof.

5. The truck structure set forth in claim 4, wherein said first beam is pivoted on said guide bogie frame at a point positioned forwardly of the mid-point between the transverse axes of said first pair of load wheels, and said second beam is pivoted on said follower bogie frame at a point positioned forwardly of the mid-point between the transverse axes of said second pair of load wheels.

6. Truck structure supporting and guiding on a pair of railway rails one end of the body of a railway car, said truck structure comprising a guide bogie including a frame, a first pair of load wheels mounted on said guide bogie frame in tandem relationship for engagement with the top of one associated rail to support said guide bogie thereon, a front pair of guide wheels pivotally mounted on said guide bogie frame in front of said first pair of load wheels for engagement respectively with the opposite sides of the one associated rail to guide said guide bogie thereon, a rear pair of guide wheels mounted on said guide bogie frame to the rear

of said first pair of load wheels for engagement respectively with the opposite sides of the one associated rail to guide said guide bogie thereon, means for resiliently urging said front guide wheels into engagement respectively with the opposite sides of the one associated rail, means for resiliently urging said rear guide wheels into engagement respectively with the opposite sides of the one associated rail, the resilient urging of said front guide wheels being greater than the urging of said rear guide wheels to provide a greater centering pressure at the leading guide wheels than at the trailing guide wheels to reduce the average forces supported by all of the guide wheels, a follower bogie including a frame, a second pair of load wheels mounted on said follower

bogie frame in tandem relationship for engagement with the top of the other associated rail to support said follower bogie thereon, linkage structure interconnecting said guide bogie and said follower bogie for coordinating the movements thereof, and mounting structure for connecting said bogies to the body of an associated railway car.

7. The truck structure set forth in claim 6, wherein said mounting structure includes a single body bolster connected both to said guide bogie frame and said follower bogie frame and connected to the body of the associated railway car.
